Fig. 1

Fig. 2

Fig. 3

*Fig. 7**Fig. 8*FIG. 1 is a partially exploded perspective view of an illuminable vanity case illustrating my new design, the case being shown in open condition, with the mirror well cover removed;

FIG. 2 is a top plan view of the case with all the covers in place;

FIG. 3 is a front elevational view of the case in the position as illustrated in FIG. 1;

FIG. 4 is a side elevational view of the same;

FIG. 5 is a perspective view of the illuminable vanity case of FIG. 1 in the closed condition and showing the upper or lid section with the cover for the mirror well in place;

FIG. 6 is an exploded perspective view of the illuminable vanity case of FIG. 5 with said cover for the mirror well removed;

FIG. 7 is a bottom plan view of the carrying case opposite the mirror well cover side; and

FIG. 8 is a rear edge plan view of the carrying case.

In FIG. 1, the center compartment is visible with a

cover therefor shown poised for placement over the mouth of the compartment. The right-hand compartment of the case illustrated in FIG. 1 is similar to the left-hand compartment, but with its cover shown poised for placement over the mouth thereof.

I claim:

The ornamental design for an illuminable vanity case, substantially as shown and described.
